PAGE 2

FIG. 2.

FIG. 3.

Figure 1 is a perspective view of my air conditioner cabinet or similar article showing my new design;

Figs. 2, 3 and 4 are top plan, front elevational and side elevational views thereof, respectively, with the conventional rear portion of the cabinet, shown in broken lines in Fig. 1, omitted for convenience of illustration.

Figure 5 is a partial detail view on a slightly enlarged scale of portions of the upper front grill and panel.

The dominant features of my design reside in the portions shown in full lines.

I claim:

The ornamental design for an air conditioner cabinet or similar article substantially as shown and described.
